ATTORNEY

UNITED STATES PATENT OFFICE.

HECTOR ALLARD, OF LAEKEN-BRUSSELS, BELGIUM.

AUTOMATIC FIRE-EXTINGUISHER.

1,108,658.

Specification of Letters Patent. Patented Aug. 25, 1914.

Application filed September 27, 1913. Serial No. 792,134.

To all whom it may concern:

Be it known that I, HECTOR ALLARD, a subject of the King of the Belgians, and residing at Laeken-Brussels, Belgium, have invented new and useful Improvements in Automatic Fire-Extinguishers; and I do hereby declare the following to be a full, clear, and exact description of the same.

My present invention relates to automatic fire-extinguishers of the class, in which a cock of a water-pipe is automatically opened and an alarm-bell automatically operated as soon as the temperature in the room, in which the apparatus is arranged is raised to a predetermined degree.

The object of my invention is to provide an apparatus of this class, wherein a rotatably arranged hammer is normally held in its inoperative position by a device of fusible material, which when melted by the heat releases the hammer so that the latter strikes the handle of a cock, which opens the water-pipe to enable water to be discharged through a lower cross-pipe arranged to rotate around the center of the fixed water-pipe under the pressure of the water. At the same time water is admitted through a narrow branch-pipe to a water-turbine, the shaft of which carries the striker of a gong or the like serving as an alarm device.

The invention will be readily understood from the following description, taken in connection with the accompanying drawing, wherein:

Figure 1.—shows the front elevation of my improved apparatus; Fig. 2.—is the top plan view of same; Fig. 3.—is a fragmentary perspective view of the bracket serving to hold the operating hammer in its inoperative position; Fig. 4.—is a fragmentary perspective view of the handle of the cock.

Referring to the drawings 1 designates a vertical pipe having its upper end 2 reduced and screw-threaded whereby the device may be readily screwed into an internally threaded branch pipe of the water-main or the like. The pipe 1 is normally closed by means of a suitable cock 3, the handle 4 of which is placed in a horizontal position (Fig. 1) if the cock is shut off. Arranged at the lower end of the pipe 1 is a suitable ball-bearing 5, supporting a rotatable socket 6, to which are secured two hollow arms 7, 8 arranged in line with each other and in opposite directions and terminating into hollow ball-shaped heads 9, 10 respectively.

The head 9 is provided with a lateral discharge-slot 11, while the head 10 is provided with an upper discharge-slot 12.

Near its upper end the pipe 1 is formed with an integral cross-piece 13 (Fig. 2), to which is secured in any suitable way a horizontal bar 14, one end 15 of which is bent forwardly at right angle and provided with two suitable brackets 16 and an intermediate opening 17 (Fig. 3). The bar 14 carries a horizontal forwardly extending shaft 18, on which is rotatably mounted a hammer 19, having tendency to turn downwardly under the pressure of a coiled spring 20 (Fig. 2) surrounding the shaft 18. Said hammer is normally held in its inoperative position by means of a small cross-piece 21 of suitable fusible material, inserted between the shank of the hammer and the brackets 16 as clearly shown in the drawing. The handle 4 of the cock 3 is held against accidental movement by means of a suitable flexible connection 22, connecting the cross-arms 23 of said handle to the fusible device 21 (Fig. 1).

Extending from a point below the cock 3 is a narrow branch-pipe 24, extending to a small water turbine 25 of any suitable well-known construction, the shaft 26 of which carries and actuates the striker of a gong 27, if the turbine is in operation. The turbine 25 is secured to the bar 14 and the gong 27 is secured to the end 28 of said bar, bent at right angles as more clearly shown in Fig. 2.

The operation of the device will be readily understood from the foregoing description and drawing: The temperature being raised above a predetermined degree, the fusible cross-piece 21 will be melted so as to release the hammer 19, which under the action of the spring 20 is suddenly turned downwardly and strikes the handle 4 of the cock 3, whereby the hammer 19 and handle 4 are brought in the positions 19', 4' respectively indicated in dotted lines in Fig. 1. In this position the cock 3 is opened and water is admitted into the rotatable arms 7, 8, whence it will be discharged through the slots 11, 12. At the same time said arms are rotated by the pressure of the water, whereby the discharged water will be uniformly distributed in the room. The cock 3 being open, water is also admitted through the branch 24 into the turbine 25, which actuates the striker of the alarm-gong 27.

The form of the water distributing arms

7, 8 and the discharge-slots 11, 12 may of course be changed as desired without departing from the scope of my invention.

Having fully described my invention, what I claim and desire to secure by Letters Patent is:—

1. In a fire extinguisher of the type specified, the combination of a pipe; a valve therein; a sprinkler communicating with the pipe; a pair of spaced brackets; and a pivoted hammer receivable between the brackets when in its raised position and adapted to strike and operate the valve.

2. In a fire extinguisher of the type specified, the combination of a pipe having a sprinkler communicating therewith; a valve having a handle in the intermediate part of the pipe; a bar secured to the pipe and having a pair of spaced upwardly hooked brackets; and a hammer having its handle pivoted on said bar and receivable between said brackets when in its raised position,

and its weight adapted to strike said valve handle.

3. In a fire extinguisher of the type specified, the combination of a vertical pipe; a sprinkler on the lower end of the pipe; a valve in the intermediate part of the pipe and having a handle; a bar secured on the upper part of the pipe and having an angularly bent end provided with a pair of upwardly hooked brackets and an upwardly curved part between the brackets; a hammer pivoted on said bar and having its shank receivable between said brackets when in its raised position, its weight being adapted to strike the valve handle.

In testimony whereof, I have signed my name to this specification in the presence of two subscribing witnesses.

HECTOR ALLARD.
